H. A. BEARD

PORTABLE TOILET

Filed Oct. 27, 1924

UNITED STATES PATENT OFFICE.

HERBERT A. BEARD, OF ROCHESTER, NEW HAMPSHIRE.

PORTABLE TOILET.

Application filed October 27, 1924. Serial No. 746,207.

To all whom it may concern:

Be it known that I, HERBERT A. BEARD, a citizen of the United States, residing at Rochester, in the county of Strafford and 5 State of New Hampshire, have invented certain new and useful Improvements in Portable Toilets, of which the following is a specification.

This invention relates to portable toilets 10 for use by campers, automobile tourists, and the like.

An object of the invention is the provision of a device of this character, which may be compactly folded and transported in a 15 motor vehicle.

A further object is the provision of a device that may be assembled without the use of independent supports, such as trees, fence posts or the like.

20 In the accompanying drawings, I have shown one embodiment of the invention. In this showing:

Figure 1 is a perspective view of the entire device,

25 Figure 2 is a plan view of the seat,

Figure 3 is a vertical sectional view on line 3—3 of Figure 2,

Figure 4 is a detail sectional view on line 4—4 of Figure 2,

30 Figure 5 is a similar view on line 5—5 of Figure 4,

Figure 6 is a horizontal sectional view on line 6—6 of Figure 3, and,

35 Figure 7 is a perspective view of a portion of the seat, inverted.

Referring to the drawings, the reference numeral 1 designates a plate or supporting member preferably made of metal or other suitable material and provided with a 40 central opening 2. In this instance, I have shown a supporting member having a straight rear edge 3 and curved side and front edges 4. The particular shape of the plate, however, is immaterial. As shown, 45 the portion of the plate surrounding the opening is rolled as at 5, providing a depending flange. The outer edge is also rolled to provide a flange 6.

The seat which may be supported by any 50 number of legs, and in this instance, I have shown three legs, pivotally connected to the seat to permit folding. At suitable intervals, the flange 6 is cut away, providing a pair of parallel members 7 (see Figures 5 and 7) adapted to receive a pivot pin 8.

Legs 9 are mounted on these pivot pins and the legs are substantially U-shaped in horizontal cross section, as shown in Figure 6 of the drawings. The top of the leg is provided with an extension 10, adapted to aline 60 with the upper surface of the seat when the leg is in operative position. As shown, the leg inclines outwardly and its outward movement is limited by a pin 11, mounted in suitable openings 12 in the extension 7. 65 To prevent accidental release of the leg, a catch 13 is pivoted thereto and is adapted to engage the pin 11. This catch is normally held in operative position by means of a spring 14. As shown, the bottoms of the 70 legs are closed by plates 15, to prevent them from sinking into the ground when the device is assembled. A covering of felt or other suitable material may be arranged over the seat, as indicated at 16. The edges 75 of this material extend over the flange 6, and are secured thereto by means of suitable laces or tie strings 17, which pass through openings 18 in the flange.

In connection with the device, I provide 80 a foldable curtain consisting of rectangular sections 19 having stiffening members or wire or other suitable material arranged in their edges, as at 20. This curtain is adapted to be arranged around the device, as 85 shown in Figure 1 of the drawings, and when the device is to be transported, the curtain may be folded in any suitable manner.

It is to be understood that the form of 90 my invention herewith shown and described is to be taken as a preferred example of the same, and that various changes in the shape, size, and arrangement of parts may be resorted to without departing from the spirit 95 of the invention or the scope of the subjoined claims.

I claim:

1. In a device of the character described, a seat member having a substantially central opening, said member being provided with a peripheral flange, said flange being extended inwardly at intervals to form spaced parallel members, legs arranged between said parallel members and pivotally 105 connected thereto, and means for locking said legs in operative position.

2. A device constructed in accordance with claim 1 wherein said pivoted legs are inclined outwardly when in operative position, 110

and a pin is arranged between said parallel members and adapted to be engaged by the adjacent leg to limit the outward movement of the leg.

3. In a device of the character described, a seat member having a substantially central opening and provided with an integral depending peripheral flange, said flange being extended inwardly at intervals to form pairs of spaced parallel members, said seat member being cut out between the parallel members of each pair, a pivot pin connected between the parallel members of each pair below the top of said seat member, and a leg arranged between each pair of parallel members and pivotally connected to said pin, each of said legs being provided with an offset portion in alignment with the top of said seat member and adapted to engage the edge thereof at the inner limit of said cutout portion to limit the outward movement of the lower end of the leg.

4. In a device of the character described, a seat member having a substantially central

opening and provided with an integral depending peripheral flange, said flange being extended inwardly at intervals to form pairs of spaced parallel members, said seat member being cut out between the parallel members of each pair, a pivot pin connected between the parallel members of each pair below the top of said seat member, a leg arranged between each pair of parallel members and pivotally connected to said pin, each of said legs being provided with an offset portion in alignment with the top of said seat member and adapted to engage the edge thereof at the inner limit of said cutout portion to limit the outward movement of the lower end of the leg, and a pin connected between the parallel members of each pair and adapted to contact with said leg when the lower end of the latter is arranged in its open position, said pin being arranged below said pivot pin.

In testimony whereof, I affix my signature.

HERBERT A. BEARD.
